(57) **CLAIM**

The ornamental design for a container lid, as shown and described.

DESCRIPTION

FIG. 1 is a top perspective view of a container lid of the present design, shown in closed configuration.

FIG. 2 is a bottom perspective view of the container lid of FIG. 1.

FIG. 3 is a right side elevation view of the container lid of FIG. 1, the left side being a mirror image thereof.

FIG. 4 is a top perspective view of the container lid of FIG. 1, shown in its open configuration.

FIG. 5 is a top plan view of the container lid of FIG. 4, shown in its open configuration.

FIG. 6 is a bottom plan view of the container lid of FIG. 4, shown in its open configuration.

FIG. 7 is a left side elevation view of the container lid of FIG. 4, shown in its open configuration; and,

FIG. 8 is a front elevation view of the container lid of FIG. 4, shown in its open configuration.

The broken lines in the drawings showing the container lid illustrate the portions of the container lid that form no part of the claimed design.

1 Claim, 3 Drawing Sheets
